Primary Examiner — Richard Edgar*Assistant Examiner* — Alexander J David(74) *Attorney, Agent, or Firm* — Oliff PLC(57) **CLAIM**

The ornamental design for an embroidery machine as shown and described.

DESCRIPTION

FIG. 1 is a front, right perspective view of the embroidery machine;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a front, top perspective view thereof.

The evenly spaced broken lines depict parts of the embroidery machine that form no part of the claimed design. The dot-dash chain lines depict a boundary of the claimed subject matter and form no part of the claimed design.

1 Claim, 7 Drawing Sheets(56)
